ARTICLE DISPLAY HOLDER

Albert H. Work, P.O. Box 736, Estes Park, Colo.

Filed Mar. 25, 1965, Ser. No. 84,504

Term of patent 7 years

(Cl. D80—9)

FIG. 1.

FIG. 2.

FIG. 4.

FIG. 3.

The dominant features of my design reside in the portions shown in full lines, the broken line representation of a portion of the vending machine in FIGURE 1 being for purposes of illustration only.

I claim:

The ornamental design for an article display holder, as shown and described.
